IRONING BOARD

Filed March 7, 1923

INVENTOR,
John N. Frace
By Ch. Kirchenbuehl
HIS ATTORNEY

UNITED STATES PATENT OFFICE.

JOHN N. FARIS, OF PORTLAND, OREGON.

IRONING BOARD.

Application filed March 7, 1923. Serial No. 623,390.

To all whom it may concern:

Be it hereby known that I, JOHN N. FARIS, a citizen of the United States, and a resident of Portland, in the county of Multnomah 5 and State of Oregon, have invented a new and useful Ironing Board, of which the following is a specification.

This invention relates more particularly to boards for ironing clothes by hand.

10 An object of my invention is to provide an exceedingly simple and efficient ironing board having great rigidity.

A further object is to provide an extensible table under the ironing board for clothes 15 about to be ironed and for supporting the overhanging edges of clothes being ironed and to prevent their touching the floor.

I accomplish these results in the manner described in the following specification and 20 illustrated in the accompanying drawing, in which:

Figure 1 is a side elevation of my ironing board of which Figure 2 is a plan and Figure 3 an end elevation showing the supporting table or trays extended. Figure 4 is a small scale side elevation showing the board folded up. Figure 5 is a section through the over-lapping ends of the sliding trays.

Similar numbers of reference refer to the 25 same or similar parts throughout the several views.

Referring in detail to the drawing, I have constructed my device of the usual ironing board 10 provided under its square end 11 30 with a pair of standards 12 to which are hinged the upright legs 13 on the rod 14. A horizontal frame consisting of the side pieces 15 and the end pieces 16 is hinged to the legs 13 by means of the rivets 17. The short 35 legs 18 are also hinged to the member 15 but at its opposite end from the legs 13 by means of the rivets 19. Cross ties 20 and braces 21 hold the legs rigid in a transverse position. The folding braces 22 hold the legs 18 40 in their proper relation to the members 15.

Across the top of the members 15 I have placed the sliding shelves or trays consisting of spaced slats 23 secured at their outer ends to the ledges 24 and at their inner ends to the 45 small cleats 25. A stationary cleat 26 which is secured on the short blocks 26^A which are secured on the member 27 holds the inner ends of the slats 23 down against the sup-

porting member 27 which is secured to the ends 16 between the members 15. 55

A stationary slat 28 between a pair of slats 23 has secured thereon a block 29 to which, by means of the hinge 30, is secured the brace arm 31 whose upper end bears against the cleat 32 on the under side of the board 10. 60 A hook 33 is provided to hold the arm 31 against the cleat 32.

A V-shaped brace 34 is hinged on the rod 14 and joined at its lower end by the cleats 35 and bears against the block 29, thereby 65 bracing the board and legs 13 in both directions. A button 36 is also provided on the under side of the member 27.

When setting up my ironing board it is only necessary to bring the legs to the position shown in Figure 1, place the braces 31 and 34 in position, fasten the hook 33 and the board is ready for work. To take same 70 down, the operation is reversed and the legs are secured in the position shown in Figure 75 4 by merely turning the button 36.

The usual pad and cloth cover have been omitted from the drawing as not forming a part of the invention.

I am aware that many forms of ironing 80 boards have been constructed in the past, I therefore do not claim same broadly but have directed my claim toward a board by special construction which permits of easy 85 setting up and folding, and more especially 85 to the extensible table under the ironing board.

What I claim as new is:

In an ironing table, the combination of a 90 board having an ironing surface and having two legs hinged to and supporting one end thereof with a horizontal frame under said board having two short legs hinged to one end and having its other end hinged to said 95 board supporting legs; brace means for supporting the other end of said ironing board over said frame; and a pair of independent sliding trays on said frame adapted to be pulled outwardly beyond the edges of said board, said trays consisting of overlapping 100 slats having cleats fastened across the inner and outer ends thereof and having a holding cleat between said inner cleats secured to said frame.

JOHN N. FARIS.
